UNITED STATES PATENT OFFICE

2,421,204

FASTENER FOR ADJOINING SHEETS
OR PLATES

William Jung, Forest Hills, N. Y.

Application September 11, 1943, Serial No. 502,037

3 Claims. (Cl. 24—221)

1

This invention relates to the patent-class of "Metallic building structures" in the sub-class "Clips or fasteners," and includes improvements over certain devices known to the inventor to be in public use and to involve needless expense of material in manufacture and of time in installing the devices; so, to facilitate an understanding of the advantageous differences between the present invention and some of the inventions above referred to, reference is now made to page 392, Fig. VIII, in a recent issue of "Aircraft Engine Maintenance"; also to a pictorial advertisement of "Shakeproof Cowl Fasteners"; both in the file of applicant's attorney in readiness to file as exhibits if required or permitted by the Patent Office; both of these prior devices being such as to require extrinsic securing means such as screws and bolts or rivets, and drilled or punched holes for receiving such fasteners; whereas, no such extrinsic fasteners and no holes therefor are needed in the present invention wherein the fastening means is intrinsic or inherent.

As a comprehensive title for this invention I have chosen to call it an improved Fastener and unfastener for adjoining sheets or plates; for although it is exceedingly practical and efficient as a cowl-fastener for airplanes, its uses are by no means limited thereto.

One object of the invention is to effect a very considerable saving in material used in the manufacture of such devices, by eliminating lateral flanges or ears for receiving rivets or bolts, hence, to eliminate the use of rivets, etc., and the expense thereof.

Another object is to effect a very considerable saving in man-hours and in power that would be required to bore or punch holes for rivets, etc., to place the rivets in the holes and to require two workmen for holding and hammering the rivets.

Another object is to provide several forms of the invention, in wire and in sheet metal, including an interchangeable feature, so that where the sheets or plates are formed for use with any one of these forms or embodiments, any other of these forms may be substituted therefor without considerable change in the construction of the two sheets or plates being fastened together.

Other objects and important features are pointed out or implied in the following details of description, in connection with the accompanying drawings in which:

Fig. 1 is top plan view of an integral spring-member of the device or combination that constitutes one embodiment of this invention.

2

Fig. 2 is a bottom plan view of the combination mentioned above and also shown in part in Figs. 3 and 4.

Fig. 3 is a view partly in vertical section along the line 3—3 of Fig. 2, the positions of parts of said integral spring-member that have been cut away being indicated in dot-dash lines, the same being true of the screw-headed catch-member.

Fig. 4 is a horizontal sectional view taken along the line 4—4 of Fig. 3, as viewed from beneath.

Fig. 5 is a sectional view similar to Fig. 3, but showing a modification in which the integral spring-member is formed of sheet metal or the like, viz., of any appropriate material that has the needed qualities of stiffness and springiness, durability etc., the section being in the plane of line 5—5 of Fig. 6.

Fig. 6 is a top plan view of the integral spring-member shown in the combination of Fig. 5.

Fig. 7 is a bottom plan view of another modification in which both the integral spring-member and the catch-member are different from those in Figs. 2, 3, 4 and 5.

Fig. 8 is a vertical sectional view taken along the line 8—8 of Fig. 7 and showing the catch-member in full side-elevation.

Fig. 9 is a top plan view of the same modification of the integral spring-member as shown in Figs. 7 and 8.

Fig. 10 is a vertical sectional view showing a modification wherein the integral spring-member has features similar to corresponding features in Figs. 6 and 9, also a dissimilar feature which eliminates a grommet where shown in Figs. 2, 3, 4, 5 and 8.

Referring to these drawings in detail, in which, similar reference numerals refer to similar parts throughout the several views, the invention is described in detail as follows:

In a broad sense, the invention resides in any one of the several forms of integral spring-members 11, 11a, 11b and 11c, any one of which is useful as an element of the combination presently described and which includes several interchangeable modifications.

The wire-spring-member of Figs. 1, 2, 3 and 4 is formed of a single piece of wire and is formed into three aligned substantially annular portions, or in a broader sense, formed with a central catch-receiving opening 12 and with springy loops 13 at opposite sides of the central opening, also with studs or stubs 14 and a substantially straight middle portion 15 which extends diametrically across the opening at a little distance therefrom and serves as a catch-engaging element for co-

operation with a catch-member or rotary catch 16, as seen in Figs. 2 and 3. The studs 14 are ends of the piece of wire bent laterally with respect to the plane in which the central opening 12 is located, and these studs project from the opposite side of the opening to that side where the element 15 is located; in other words, they project away from the plane of the element 15 and from the plane of the arcuate elements 17 that outline the opening 12.

In broad terms, the stiff spring-member 11a is formed from a blank of sheet-material (preferably but not essentially metal), and its central opening (that corresponds to 12 in Fig. 1) is seen between the inner edges 17a on which the studs are turned outward or upward, as shown in Figs. 5 and 6, and these studs or stubs project away from the straight catch-engaging element 15a. The springy loops 13a functionally correspond to the loops 13 of Fig. 1.

In Figs. 7, 8 and 9, the stiff spring-member 11b is of a blank of any appropriate springy sheet material, having its opening 12b between arcuate margins 17b and having studs 14b upturned from its margins (Fig. 9). One of its springy loops is shown at 13b, and its other at 13bb where the ends of the sheet-blank are interlapped to be united by any appropriate means, or left disunited. In axial alinement with the opening 12b there is a second opening 18 that includes opposite recesses or passages 18b, and at opposite edges of this opening are provided catch-engaging elements each including a cam-like or wedge-like portion 19 and a concave seat 20, these being substantially the same as are shown in the slightly modified form of Fig. 10.

In Fig. 10, the elements 17c correspond to 17a of Fig. 6, the elements 14c correspond to the elements 14a and 14b, but have the additional purpose of securing the spring-member 11c to the lower plate 21c that corresponds to the plate 21 in Figs. 2, 3, 4, 5, 7 and 8; for whereas all these lugs, stubs or studs 14 to 14c are disposed in recesses, 22 and 22c to prevent or limit turning of the spring members 11 to 11c, only the studs 14c are outwardly inclined and engage with outwardly inclined walls of the recesses 22c for also securing this spring-member 11c to the lower plate of the two that are to be secured together, thus eliminating the expense of obtaining and installing 50 grommets 23 which are employed to secure the spring-members to the sheets or plates 21 in Figs. 2, 3, 4, 5, 7 and 8.

In addition to the members and elements mentioned in the foregoing, there is an upper or outer plate or sheet 24 having a catch-receiving opening 25 for receiving the intermediate portion of a screw-headed catch-member or rotary catch 16 (Figs. 2, 3, 4, 5) or 16a (Figs. 7 and 8). Each of these members 16 and 16a is provided with a shallow annular groove 26 adjacent to its head for receiving the margin of the hole 25 in which it is easily turnable by turning the screw-head thereof, whereas, the immediately lower part of the member 16 or 16a is normally slightly larger than the hole 25; however, to facilitate assembling these members 16 or 16a with the sheet or plate 24, they may be taken from a refrigerator where they are contracted to a considerable extent, and quickly forced through the slightly smaller catch-receiving opening or hole 25 until the margin of the hole is in the shallow groove 26, whereupon, though the catch-member or rotary catch can be easily rotated in the hole 25, it cannot become accidentally removed from said hole by the mere

action of gravitation or by other than a very strong pressure in the opposite direction from that of its insertion in said hole.

From the foregoing, it will be seen that the combination of this invention consists of two units adapted to be fastened to one another and separated from one another, one of these units comprising a plate or sheet 21 or 21c permanently united with a spring-member 11, 11a, 11b or 11c; and the other unit comprising the plate 24 and the catch-member 16 or 16a permanently secured to one another; these two units being secured to one another by the slightly different means shown in the modified forms, viz., in Figs. 2, 3, 4 and 5, the catch-member 16 is placed with its middle portion extending through the eyelet or grommet 23 or 23a when in such position that its bifurcated lower end straddles the element 15 or 15a, and then the user turns the screw-head of the catch-member 16 clockwise, thereby causing the catch-elements 27 to slide under the springy catch-engaging element 15 or 15a until the latter comes to rest in the depressed seat 28 when the rotary movement of this catch member 16 has continued through substantially 90 degrees, to the position shown in Figs. 2 and 3, wherein the plates 21 and 24 are not only securely but removably or separably fastened to one another, and it is only necessary to reverse the rotation of the catch-member to the position shown in Fig. 5 when desired to unlatch or unlock the catch-elements 27.

The catch-member 16a is provided with radially projecting studs or catch-elements 29, and the recesses 18b and 18c are passages for these catch-elements to pass through to points near the wedge-like elements 19. When the studs 29 are moved out of their seats 20, by a contra-clockwise movement of the catch-member 16a, these studs can be passed outward through the passages 18c when the rotary movement has continued through about 90 degrees, so the sheets or plates 21 and 24 can then be separated, for passages 30 are provided in the plate 21 and 21c and in the grommet or swaged fastener 18b.

Although these several embodiments of my invention are described specifically, I have no intention to limit my patent protection to these precise details, for the invention is susceptible of numerous changes within the scope of the inventive ideas as implied and claimed.

I claim the following as my invention:

1. In a spring-member of a device for fastening sheets or plates to one another, said spring-member having a central substantially circular opening and having springy loops at opposite sides of said central substantially circular opening and having a stub projecting away from a plane in which the marginal elements of the central opening lie, said stub being insertable into a lateral recess of a catch-receiving opening in one of said sheets or plates for preventing undue rotary movement of said spring-member with respect to said one of the sheets or plates, said spring-member including a catch-engaging element that is yieldingly supported by said springy loops and is spaced from said central opening so as to be movable toward and from said central opening when cooperating with a catch of the type described, said catch-engaging element being at least partly across said central opening and disposed substantially along a diametral line of the latter.

2. In the spring-member defined by claim 1, said springy piece of metal or the like being a length of wire whose end portions comprise said

marginal elements around the central opening and whose middle part crosses said opening and constitutes said catch-engaging element, and said stub being turned laterally from one of said end- portions of the length of wire.

3. In combination with the spring-member defined in claim 1, a sheet or plate having an opening therethrough for receiving a rotary catch for cooperation with said catch-engaging element in securing this sheet or plate to another sheet or plate, and means engaged with the margin of the last-said opening and cooperative with said stub for fixedly securing said spring-member to the first-said sheet or plate independently of extrinsic securing means.
